ABSTRACT OF THE DISCLOSURE

An apparatus for counting sheets of paper arranged in stacks and for determining when a specified number of sheets have been counted. Each stack is detected and a signal representative of the stack enables a pulse generator which produces a pulse corresponding to each sheet of paper. The output of the pulse generator is coupled to a binary counter and associated matrix which determines when the number of pulses corresponding to the number of sheets in a stack is produced and causes a reset pulse to disable the pulse generator until the next stack is detected. The gated oscillator is also coupled to a decade counter which counts the total number of pulses produced or determines when the number of sheets that comprise a batch have been counted.

This invention is concerned with a counter for counting articles, such as sheets of paper, arranged in stacks and emanating from a source.

When paper is processed, for whatever use, there is usually some point in the process in which the paper is cut from rolls into sheets. It is essential to have an accurate count of the sheets cut. Frequently the paper from several rolls is fed to the cutter at the same time, thereby allowing the cutter to cut several rolls at once. The cut paper will emanate from the cutter in stacks, the number of sheets in each stack being equal to the number of rolls feeding the cutter. By ordinary detection means, such as a photocell, only the stacks of paper can be detected, not the individual sheets of paper in each stack. Therefore, to provide an accurate count of the sheets cut the detected output of the cutter must be multiplied by the number of sheets in each stack. Prior multipliers of the type that can be used in a paper counter have not been entirely satisfactory in that they have not provided a completely accurate and dependable count or they have required costly special tubes or they have suffered other defects.

It is an object of the present invention, therefore, to provide a new and improved counter for paper or other articles.

It is a further object of the present invention to provide a new and improved paper counter for counting sheets of paper arranged in stacks.

It is still a further object of the present invention to provide a new and improved pulse multiplier.

In accordance with the present invention a counter for determining the total number of articles that pass a given point, the articles being arranged in stacks with a known number of articles in each stack comprises means for detecting each stack of articles and generating a signal representative of each stack. The invention further comprises gated means for producing pulses each of which is representative of an article and means for rendering the gated means operative upon the application of each signal representative of a stack of articles and means for determining when the number of pulses that corresponds to the number of articles in a stack has been produced. The apparatus also comprises means responsive to the determinative means for generating a signal to render the gated means inoperative, when the number of pulses that corresponds to the number of articles in a stack has been

2

produced and a counting circuit for counting the total number of pulses produced by the gated means, the total number of pulses being equal to the number of stacks detected, multiplied by the number of articles in each stack.

For a better understanding of the present invention together with other and further objects thereof, reference is had to the following description taken in connection with the accompanying drawings, and its scope will be pointed out in the appended claims.

Referring to the drawings:

FIG. 1 is a block diagram representation of one embodiment of a paper counter constructed in accordance with the present invention, and

FIG. 2 is a block diagram representation of a binary counter switching matrix and AND circuit of use in the FIG. 1 embodiment.

Description of FIG. 1 counter

In FIG. 1 of the drawings there is shown a paper counter for determining the total number of sheets of paper that pass a given point, the sheets being arranged in stacks with a variable known number of sheets in each stack, and for dividing the counted sheets into batches of known quantity. For example, it might be desired to provide a continuous count of the number of sheets cut and then provide an indication that a batch of say five hundred has been cut. As illustrated, the paper counter comprises means for detecting each stack of paper and for generating a signal representative of each stack, shown as light source 15 operating in conjunction with photocell 16. The light source 15 and photocell 16 are so arranged that each stack of paper must pass between them. The light supplied to the photocell 16 by source 15 is thereby interrupted and reappplied when the stack of papers is passed completely between them, generating a signal representative of that stack. The paper counter also includes gated means for producing pulses each of which is representative of a sheet of paper, shown as gated oscillator 17. Oscillator 17 is constructed to produce only half-cycle outputs, each half-cycle output representing a sheet of paper.

The system further comprises a bistable device for rendering the gated oscillator 17 oscillatory upon the application of each signal generated by the photocell 16 and nonoscillatory upon the application of a reset signal, shown as flip-flop 18. Flip-flop 18 could be any bistable device, such as a bistable multivibrator, a relay, or any similar device.

The counter further comprises means 19 for determining when the number of pulses that corresponds to the number of sheets in a stack has been produced. As shown, determinative means 19 includes binary counter 20 for counting the pulses produced by the gated oscillator 17.

In a practical system this would normally be a four stage binary counter, as there would generally be no more than fifteen rolls of paper feeding the cutter 14. Determinative means 19 also includes first switching matrix 21 for permitting the selection of the desired output of the gated oscillator 17. Determinative means 19 also includes AND circuit 22 for determining when the value selected by the first switching matrix 21 is equal to the value in the binary counter 20. The binary counter 20, the switching matrix 21 and AND circuit 22 will subsequently be explained in greater detail.

The system further includes first means responsive to AND circuit 22 for generating a reset signal when the number of pulses that corresponds to the number of sheets in a stack has been produced, shown as reset generator 23.

This reset generator 23 can be any device that provides a pulse output suitable for resetting the flip-flop 18 and the binary counter 20.

The system also includes a counting circuit for counting the total number of pulses produced by the gated oscillator 17, shown as decade counter 24. As shown, the decade counter 24 is actually composed of three-decade stages, the units decade counter 25, the tens decade counter 26, and the hundreds decade counter 27. Additional stages could be added as required to achieve the desired count. These counters are capable of being reset when the pulses that correspond to the desired number of sheets in a batch have been produced. It should be noted that binary counter 20 counts the pulses that represent the number of sheets in a stack, while decade counter 24 counts the pulses that represent the number of sheets in a batch.

The system also includes a second adjustable matrix for permitting the selection of the quantity of sheets that are to comprise a batch, shown as switching matrix 28. As shown, the switching matrix 28 actually consists of three separate switching units 29, 30 and 31, one corresponding to each of the decade stages of the counting circuit 24. Each of these switching units is exactly the same as the first switching matrix 21 and also includes an AND circuit which performs the same function as AND circuit 22. Each switch can be adjusted so that an operator can select the units, tens and hundreds components of the desired number of sheets that are to comprise a batch.

The system also includes a second comparison circuit for determining when the selected batch quantity is equal to the quantity indicated by the counting circuit 24, such as AND circuit 32. AND circuit 32 has a connection to each switching unit and only produces an output when the counters contain the selected number.

The system also includes a second reset generator 33 responsive to AND circuit 32 for generating a reset signal that indicates that a number of sheets sufficient to comprise a batch have been counted. Structurally, reset generator 33 can be of the same type as first reset generator 23. The function of reset generator 33 is to provide a signal for resetting decade counters 25, 26 and 27, to advance the batch counter 34 one position and to provide or control the production of an output signal which is to be used to control the separation of the batches and perform any other desired function. In the embodiment shown the reset generator triggers the relay 35 for the period of the reset pulse. In this manner an output signal is provided for a period of time sufficient to control the separation of the batches and perform any other desired function. This signal can be used to alert an operator, to activate a mechanism or in any other manner to achieve the desired separation of batches.

Description of FIG. 2

FIG. 2 is a more detailed description of binary counter 20, switch matrix 21 and AND circuit 22. Gated oscillator 17 has been rendered oscillatory by the input from the photocell 16 triggering flip-flop 18. The pulse outputs of the gated oscillator 17 are coupled to flip-flop 40, the first stage of counter 21. As the count advances, the pulses coupled to flip-flop 40 cause flip-flops 40, 41, 42 and 43, that comprise counter 21, to be placed in the state that corresponds to the number of pulses produced. The switch control 44 of switching matrix 21 is manually placed in the position that corresponds to the number of sheets known to be in each stack, thereby causing the four wipers 45, 46, 47 and 48 of the switch 21 to be placed in the proper position. For example, if there are ten rolls of paper feeding the cutter, the switch control is adjusted for the number ten, causing the wipers 45, 46, 47 and 48 to be placed in the position shown in FIG. 2. When the counter 21 has counted ten pulses and only when it has counted ten pulses, there will be a logical one applied from each wiper to AND circuit 22 thereby causing an output to be coupled to the reset generator 23. A reset pulse is generated which resets flip-flop 18 rendering gated oscillator 17 nonoscillatory and resets the counter 21 to await the next series of pulses.

4 Mode of operation

As explained above, a paper counter of this type can be used for counting sheets of paper simultaneously cut by a paper cutter 14 from a plurality of rolls of paper 13. After being cut the paper is usually fed down a conveyor where the stacks of paper will tend to spread out. Somewhere along the length of this conveyor the light source 15 and photocell 16 are placed on opposite sides of a portion of the conveyor so that the light from the light source 15 is directed at the photocell 16. When a stack of papers passes between the light source 15 and the photocell 16 the light to the photocell 16 is interrupted thereby generating a signal representative of a stack of papers. This signal is coupled to flip-flop 18 placing it in the set condition. Flip-flop 18 being in the set condition causes gated oscillator 17 to oscillate producing half-cycle oscillations or pulses. Each of these pulses, representing a single sheet of paper, is coupled to the decade counter 24 to be counted. At the same time these pulses are also coupled to the binary counter 20. As previously explained, when the pulses produced, as determined by the binary counter 20, equal to the number of sheets in a stack, as determined by switching matrix 21, an output is coupled from AND circuit 22 to reset generator 23. A reset pulse is generated which resets the flip-flop 18 thereby cutting off the oscillator and resets the binary counter 20 until the next stack of papers is detected. Therefore, in effect, the number of stacks of paper is effectively multiplied by the number of sheets in each stack.

The output of the gated oscillator 17 coupled to the decade counter 24 causes the counter 24 to advance one position for each pulse produced. These counters are of a standard type. When the first stage 25 reaches a count of ten it resets itself and the overflow is coupled to the second stage 26 advancing it one position. The same process is repeated between the second and third stages so that a true decimal number is counted by this decade arrangement. Higher numbers can be counted by adding more decade stages.

Corresponding to each decade stage are switching matrix and AND circuits of the same type as shown in FIG. 2. The number of sheets that are to comprise a batch is selected by rotating each of these switches to the proper position. When each stage of the decade counter 24 contains the number selected, as determined by the switching matrix 28, an output is produced from AND circuit 32. This output is coupled to reset generator 33 where a reset pulse is produced. This reset pulse performs several functions. It resets the decade counter 24 to zero so that the counter will count out a new batch of papers. It can be coupled out to the paper cutter 14 to alert an operator or to actually control the separation of the batches. In the embodiment of FIG. 1 it is assumed that there are power requirements of this control signal which the reset pulse cannot supply so that the reset pulse is coupled to relay 35 which will provide an output of the desired level. If an output of duration other than the duration of the reset pulse is desired an intermediate timing stage is added. The reset pulse is also coupled to batch counter 34 to advance this counter one position each time a new batch of papers is counted. The number of batches will be equal to the total number of sheets counted divided by the number of sheets in each batch.

While there has been described what is at present considered to be the preferred embodiment of this invention, it will be obvious to those skilled in the art that various changes and modifications may be made therein without departing from the invention and it is, therefore, aimed to cover all such changes and modifications as fall within the true spirit and scope of the invention.

What is claimed is:

1. A counter for determining the total number of articles that pass a given point, said articles being arranged

in stacks with a known number of articles in each stack, comprising:

means for detecting each stack of articles and generating a signal representative of each stack;
gated means for producing pulses each of which is representative of an article; 5
means for rendering said gated means operative upon the application of each signal representative of a stack of articles;
means for determining when the number of pulses that corresponds to the number of articles in a stack has been produced; 10
means responsive to said determinative means for generating a signal to render said gated means inoperative, when the number of pulses that corresponds to the number of articles in a stack has been produced;
and a counting circuit for counting the total number of pulses produced by said gated means, the total number of pulses being equal to the number of stacks detected, multiplied by the number of articles in each stack. 20

2. A counter as specified in claim 1 wherein the known number of sheets in each stack can be varied and wherein the means for determining when the number of pulses 25 that corresponds to the number of sheets in a stack has been produced is adjustable.

3. A paper counter for determining the total number of sheets that pass a given point, said sheets being arranged in stacks with a variable known number of sheets 30 in each stack, and for providing a signal indicating that the number of sheets that comprise a batch have been counted, comprising:

a light source and photocell arranged in spatial alignment so that each stack of sheets of paper passes between said light source and photocell generating signals individually representative of each stack; 35
a gated oscillator for producing pulses each of which is representative of a sheet of paper;
a bistable device for rendering said gated oscillator oscillatory upon the application of each signal generated by said photocell and nonoscillatory upon the application of a reset signal; 40
a binary counter for counting the pulses produced by said gated oscillator which is resettable when the pulses that correspond to the number of sheets in a stack have been produced; 45
a first adjustable matrix for selecting the desired output of the gated oscillator;
a first comparison circuit for determining when the value selected by said first matrix is equal to the value in the binary counter; 50
a first reset generator responsive to said comparison circuit for generating a reset signal when the number of pulses that corresponds to the number of sheets in a stack has been produced, said reset signal suitable for resetting said bistable device and said binary counter; 55
a decade counter for counting the total number of pulses produced by said gated oscillator, which is resettable when the pulses that correspond to the 60

desired number of sheets in a stack have been produced;

a second adjustable matrix for selecting the quantity of sheets that are to comprise a batch;
a second comparison circuit for determining when the selected quantity is equal to the quantity indicated by said counting circuit;
a second reset generator responsive to said comparison circuit for generating a signal indicating the sheets that comprise a batch have been counted, said signal being coupled back to reset the decade circuit to zero, being used to advance a batch counter one position and also being available as an output signal for use in the separation of batches.

4. A counter for determining the total number of sheets of paper that pass a given point, said sheets being arranged in stacks with a known number of sheets in each stack and for providing a signal indicating that the number of sheets that comprise a batch have been counted; comprising:

means for detecting each stack of sheets of paper and generating a signal representative of each stack;
gated means for producing pulses each of which is representative of a sheet of paper;

means for rendering said gated means operative upon the application of each signal representative of a stack of sheets of paper;

means for determining when the number of pulses that corresponds to the number of sheets in a stack has been produced;

means responsive to said determinative means for generating a signal to render said gated means inoperative, when the number of pulses that corresponds to the number of sheets in a stack has been produced;

a counting circuit for counting the total number of pulses produced by said gated means, the total number of pulses being equal to the number of stacks detected, multiplied by the number of sheets in each stack;

means for permitting the quantity of sheets that are to comprise a batch to be selected;

a comparison circuit for determining when the selected quantity is equal to the quantity indicated by said counting circuit;

and means responsive to said comparison circuit for generating a signal indicating the sheets that comprise a batch have been counted, said signal being coupled back to reset the counting circuit to zero, being used to advance a batch counter one position, and also being available as an output signal for use in the separation of batches.
